2 Claims. (Cl. 340—173)

The invention relates to an autodialler for a telephone substation which utilizes an information storage device comprising a two coordinate arrangement of capacitors each being connected between a particular pair of electrical conductors, one conductor out of a first set and the other conductor out of a second set. The principle of such an arrangement is known, for example, from the U.S. Patent No. 2,695,398.

In telephone systems it is known to establish automatically the frequently required connections to a restricted number of subscribers' stations by the temporary actuation of rapid-call-keys forming part of the autodialler. Such types of conventional arrangements, which are allotted, for example, to telephone subscribers in order to facilitate the dialling of frequently required subscribers' numbers, are hereinafter referred to as "autodiallers."

In the conventional types of autodiallers the cancellation of one subscriber's number and the replacement of this number by another one calls for a circumstantial alteration to be carried out in the autodialler, for example, change of wirings or soldered connections which in most cases can only be carried out by skilled personnel.

It is the object of the invention to provide an autodialler in which the preparatorily stored information can be quickly cancelled and replaced without requiring any skilled labor, and without having to perform any soldering operations. The information, however, is thereby not restricted to subscribers' numbers. In fact, also numbers or any other information capable of being expressed by digits or numerals can be preparatorily stored and used as often as required in the same and unchanged form. This information, however, is also capable of being easily cancelled and replaced by another information.

In known storage arrangements, ferro-electric condensers are used, each ferro-electric condenser constituting a cell of a two dimensional memory array. They may for instance be constructed by using a slab of ferro-electric material, such as barium titanate, and by providing two sets of parallel strip electrodes, one set on each face of the slab and the strips of the second set being perpendicular to those of the first. In this way, any ferro-electric cell defined by the intersection of two strip electrodes can be selected in a well known manner so that the corresponding condenser can be saturated in one particular direction.

In accordance with one characteristic of the invention, the autodialler utilizes an information storage device having two fixed electrodes at each crosspoint between a conductor of a first set and a conductor of a second set which are closely spaced from one another, the first connected to the conductor out of said set, and the second connected to the conductor out of said second set, and that at least for some of the crosspoints there are provided dielectric pieces and/or third electrodes closely spaced from the fixed pair of electrodes, whereby, depending on the presence or absence of said dielectric pieces and/or said third electrodes and/or whether the latter are grounded or floating, the effective capacitive coupling between the two conductors may assume one or the other out of two substantially distinct values.

In accordance with another characteristic of the invention, an information storage device as characterized

2

above is further characterized in that said dielectric pieces and/or said third electrodes are mounted on slide strips which may, for instance, be parallel to the conductors out of said first set, and which slide strips may be positioned near corresponding pairs of said fixed electrodes.

With such an arrangement as described above, one obtains a particularly inexpensive semi-permanent storage device which is essentially mechanical but static. Each conductor out of the first set may constitute an input conductor, and depending on the positions of the intermediate electrodes or dielectric pieces along the slide strip corresponding to this input conductor, the input energy will be selectively coupled to combinations of conductors of the second set via capacitive couplings, whereas very little energy will reach the remaining conductors out of the second set via the residual capacitive couplings. Thus, numbers may simply be registered, for instance, by arranging electrodes along these strips. Once the strips are inserted, the numbers are permanently stored and can never vanish in normal circumstances.

The numbers can be modified at any time by merely removing a strip from its position and replacing it by a new one bearing the new number in the form of a combination of electrodes on its surface.

25 The circuit arrangement for such an autodialler according to the invention comprises several rapid-call-keys, to each of which a predetermined randomly interchangeable information is assigned, which is composed of individual information contents, for example, a subscriber's telephone number, or a multi-digit number with a different information content, and is characterized by the fact that to each rapid-call-key, via an associated marking lead, a code converter is assigned which is provided with interchangeable groups of capacitive couplings for the respective information assigned to the individual rapid-call-keys (for example, subscribers' numbers) and which code converter serves to represent the individual information contents (digits of the subscribers' numbers) constituting the total information, in another type of code, preferably in the form of a binary number.

40 The capacitive information-storage device according to the invention, serving as the code converter, comprises for each rapid-call-key as many interchangeable groups of coupling capacities as individual information contents—e.g., number of positions in the case of subscribers' numbers—are contained in the total information assigned to the respective rapid-call-key.

45 Preferably, for the representation of each individual information content—e.g., for each digit in the case of multi-digit subscribers' numbers—in the actually known way in the form of a binary digit, four evaluation amplifiers are provided which, in accordance with the selected code, are capable of being marked in the code converter by the operation of a rapid-call-key via the assigned capacitive couplings.

50 In the further embodiment of the invention a pulse generator (source of impulses) is provided which is controlled by a chain of counting relays and transmits trains of impulses, corresponding to the individual information contents (digits of the subscriber's call number). These are stored in the evaluation amplifiers in accordance with their marking, by simultaneously stepping-on the chain of counting relays until the position of this chain coincides with the marking of the evaluation amplifiers.

55 In particular, this process can be effected either by stepping-on the chain of counting relays until it reaches the final value of its position, or by inversely controlling the chain until it reaches its zero-position.

60 The above and other objects and characteristics of the invention will become more apparent by referring to the following detailed description of preferred embodiments

of the invention to be read in conjunction with the accompanying drawings and which represent:

FIG. 1 a diagram of a crosspoint between two fixed electrodes;

FIG. 2 a cross-sectional view of a crosspoint showing the insertion of a dielectric provided by a sliding strip;

FIG. 3 a cross-sectional view similar to that of FIG. 2 but wherein a sliding strip is covered by an electrode;

FIG. 4 a cross-sectional view similar to that of FIG. 3 but wherein the electrode borne by the sliding strip is 10 grounded;

FIG. 5 a diagram of a sliding strip;

FIG. 6 a plan view of a crosspoint when the fixed electrodes are on the same side of a plate of insulating material;

FIG. 7 a cross-sectional view of several crosspoints of the type shown in FIG. 6, including a sliding strip;

FIG. 8 an electrical circuit representing the couplings between the input electrodes and the output electrodes of the memory;

FIG. 9 an electrical circuit equivalent to that of FIG. 8 when one of the input electrodes is driven by a signal;

FIG. 10 an electrical circuit rigorously equivalent to that of FIG. 9;

FIG. 11 an electrical circuit representing an arrangement of electronic gates in the form of a tree network designed to drive the input electrodes of the memory;

FIG. 12 an electrical circuit equivalent to that of FIG. 4, when a set of gates is rendered conductive in order to transmit the input signal towards one of the output terminals;

FIG. 13 the circuit of one of the gates symbolically represented in FIG. 11;

FIG. 14 the circuit of a gate necessitating less elements than that represented in FIG. 13;

FIG. 15 a circuit of the capacitive network interconnecting an input electrode of the memory to an output electrode at a crosspoint rendered effective by the insertion of a sliding strip;

FIG. 16 an electrical circuit equivalent to that of FIG. 15;

FIG. 17 a circuit similar to that of FIG. 16, taking into account the parasitic capacitances placed in parallel on the load, at one of the output points, due to the coupling between other crosspoints than the one considered;

FIG. 18 a circuit equivalent to that of FIG. 17;

FIG. 19 the circuit of a detecting system permitting to operate a relay upon the appearance of a signal at a corresponding output point of the memory;

FIG. 20 the circuit of an autodialler according to the invention with respectively one evaluation amplifier for a four-digit binary code;

FIG. 21 the circuit of an autodialler with one common evaluation amplifier operating in a timely succession;

FIG. 22, an exemplified arrangement of the capacitive translator and the coating plates used as capacitive coupling elements;

FIG. 23 the cross-sectional view of one line of the capacitive translator;

FIG. 24 the exemplified form of a slide; and

FIG. 25 a coupling plate capable of being applied to the slide according to FIG. 24.

By referring to FIG. 1, the latter shows an input electrode 1 of the capacitive memory and an output electrode 2, which is located in a plane parallel to that of electrode 1 but which is arranged perpendicularly to the latter. At the crosspoint 3 between these two fixed electrodes 1 and 2, which are only partially represented, one may insert a sliding strip (not shown in FIG. 1) made of insulating material in such a way that the dielectric constant of this material shall be able to produce a considerable change of the effective capacitance between the fixed electrodes 1 and 2. One may, for instance, provide as many sliding strips as there are fixed electrodes 1 and arrange them parallel to these, between the corresponding electrode 1 and the various fixed electrodes 2 which it will cross.

FIG. 2 shows a cross-sectional view of a crosspoint and it is seen that in the volume comprised between the two fixed electrodes 1 and 2 passes a sliding strip 4. If one assumes a unitary distance between the two fixed electrodes 1 and 2, and that the thickness of the dielectric of the strip 4 is equal to x , the ratio between the initial capacitance in the absence of the strip 4, and the coupling capacitance present due to the insertion of the strip 4 whose dielectric contact is k , will be equal to

$$1 - x + \frac{x}{k}$$

Hence, at the crosspoint where the dielectric is provided by strip, it will be possible to obtain a considerably higher capacitance than that offered at the crosspoints where the dielectric is not present, for instance, due to an opening provided in the strip. The thicker the dielectric and the higher its constant, the greater will be the capacitance. Consequently, it will be advantageous that the strip, at any rate at the crosspoints where a coupling capacitance is desired, should be as thick as possible. As it has been remarked already in the introductory part of the description, the strip may also bear electrodes.

This possibility is schematically represented in FIG. 3 where it is seen that the strip 4 is covered on its two opposite faces and at the desired crosspoints by the electrodes 5 and 5' which are interconnected on the side of the strip by a metallic part 6 so that the electrodes 5 and 5' actually form only a single electrode. In this case, at the crosspoints where the coupling strip offers the electrodes 5, 5' and 6, the increase of the coupling capacitance will be solely a function of x , the thickness of the strip, the dielectric constant k of the latter having no influence, except at the crosspoints where the coupling electrodes are not provided. In the case of FIG. 3, the outside surface of the electrodes 5 and 5' mounted on the strips will be advantageously coated by an insulating varnish in order to avoid any metallic contact between these electrodes and the fixed electrodes 1 and 2. Moreover, one may also coat the latter with a suitable varnish on their surface which is on the side of the electrodes 5 and 5'. If the strips occupy practically all the thickness of the space between the fixed electrodes, the coating of all the metallic surfaces by a varnish will permit to reduce the wear of these.

FIG. 4 shows an arrangement similar to that of FIG. 3, but wherein the electrodes 5, 5' and 6 supported by the strip are grounded. This connection to ground permits to obtain a small capacitive coupling at the crosspoints where the strip bears the electrodes 5, 5' and 6, but the grounding of these electrodes naturally necessitates a contact between these electrodes mounted on the strip and fixed terminals.

FIG. 5 shows in a schematic form an example of strips which may be inserted parallel to the input electrode strips and which are divided into ten elemental square surfaces each corresponding to a crosspoint between these input electrodes and the various output electrodes which are perpendicular thereto. There are ten crosspoints corresponding to ten successive squares on the strip where the shaded parts correspond to coupling electrodes such as 5. The strip is divided into two series of five successive squares and in each series there are two electrodes, permitting to signal an identity of the input electrode by signals appearing at the output electrodes based on the use of a 2 out of 5 code raised to the second power. In this way, each of the input electrodes may be characterized by a particular code out of a hundred possible codes. A system of this capacity may, for instance, serve as class of line indicator in a telephone exchange. The number of lines using this common translator may be variable and in particular exceed the number of different possible codes. For instance, it will be possible to realize a memory provided with a thousand strips such as that shown in FIG. 5, in order to be able to characterize the class code of one thousand lines. At any desired moment

one will be able to change the class of the line by a simple replacement of the removable strip corresponding to this line.

It is to be noted that if the strips such as shown in FIG. 5, may be indifferently inserted by one end or the other, it will not be necessary to provide a stock of one hundred types of different strips. By taking into account that ten out of a hundred codes will be symmetrical with respect to a longitudinal reversal of the strip, the number of different strips will only be equal to fifty-five instead of one hundred. One may still envisage the subdivision of each strip into several parts of the longitudinal sense, so as to reduce the number of different strips. For instance, one may envisage the insertion of these strips from two opposite sides of the memory and divide the strip into two parts each having a length of five units. In this case, and by also taking into account the fact that the half-strips may be inserted either in one direction or in the other, it will only be necessary to provide six different types of strips which will permit, by association of two halves end to end, to realize a hundred different codes. Another possibility for reducing the number of different types of strips and which does not necessitate the subdivision of the strips, will be explained later in relation with another particular embodiment which will now be described.

FIG. 6 represents an elemental crosspoint surface having substantially the shape of a square and comprising the fixed electrode 1 which is only partially represented, as well as the fixed electrode 2 for which also, only a part is shown. The fixed electrode 1 extends in a horizontal direction in the form of a strip 7 relatively narrow, and at each crosspoint with the fixed electrodes extending in another direction, a triangular surface 8 is foreseen which occupies substantially half the square constituting the crosspoint. These fixed electrodes 1 may preferably be obtained in the form of a circuit printed on a base plate. On the same side of the base plate as the fixed electrodes, one will also print the half surfaces of the other fixed electrodes 2, and as indicated by the strip 9 in dotted lines, one will print on the other side of the insulating plate a vertical conductor permitting to interconnect the triangles 10 in order to constitute the fixed vertical electrodes 2, after having established an electrical connection 11 between triangles such as 10 and the conductor 9 located on the other side of this plate. This electrical connection 11 through the base plate may be performed by any appropriate method such as that permitting to obtain a metallic coating of the hole. In particular, one may use a recent technique fore-seeing the use of connecting eyelets. Alternatively, the triangles 10 may be provided with an upturned edge along their vertical side edge which will pass through a corresponding slit in the base plate. The parts of these upturned edges appearing on the other side of the plate may then be electrically interconnected by vertical columns. Whatever the method used, there will be advantage in not producing too great additional thickness, if it is desired to stack a plurality of base plates in a restricted volume.

At the crosspoint shown in FIG. 6, in the absence of any other coupling means, one would have a capacitive coupling between the metallic surfaces 8 and 10 which will be relatively small since these two surfaces constituting the fixed electrodes are no longer in front of one another but one next to the other and in the same plane. By the use of strips such as shown in FIG. 5, and extending either horizontally or vertically, when electrode borne by the strip and having a substantially square shape, will come to rest above a pair of triangular surfaces 8 and 10, and at a short distance thereof, in order to cover them, a relatively high capacitive coupling will be obtained between the fixed electrodes 1 and 2. In this way, the dielectric constant of the strip is practically without influence and it is only necessary to provide metallic electrodes on one face of the strip, i.e., that which faces the fixed electrodes 8 and 10.

As the coupling electrodes must now be provided only on one face of the strip, the opposite face of the strip may eventually be used to inscribe a different code. In this manner, by turning the face of the strip one may obtain a different code. Hence, in case of a stock of strips such as shown in FIG. 5 and which should provide a hundred codes, by taking into account the possibilities of the reversal of the direction of insertion of the strip and of the turning of the face thereof, it will only be necessary to provide twenty-eight types of different strips. Of course, at the crosspoints where the strip face contiguous to the electrodes 8 and 10 does not present a metallic coating, while at this spot the opposite face of the strip presents an electrode, the latter should not introduce an appreciable coupling between the fixed electrodes 8 and 10. This may be obtained by a suitable thickness of the strip so that when the electrodes borne by the latter are not on the side of the fixed electrodes, they do not introduce an appreciable coupling.

By referring to FIG. 7, the latter shows a partial cross sectional view of an arrangement such as represented in FIG. 6. It is seen that the strip 4 slides parallel to the electrodes such as 8 and 10 in such a way that the electrode such as 12 carried by the strip come to cover the triangular electrodes 8 and 10 so as to obtain an effective capacitive coupling between this which is much larger than when the strip does not carry a square electrode such as 12. The fixed electrodes are mounted on a base plate 13 made of insulating material and of the type used for the realization of printed circuits. FIG. 7 does not represent the connections 9 serving to interconnect the electrodes 10 on the lower surface of the base plate 13. A metallic screen 14 has also been provided and during the stacking of several plate arrangements such as 13, the screens such as 14 and 14' which will be grounded allow to obtain a decoupling effect between the circuits belonging to the superposed plates. A suitable insulation will be provided between these screens and the connections 9, for instance, by using a varnish or depressions in the screen corresponding to these connections.

But these screens 14 have also a decoupling effect with respect to the electrodes carried by a single base plate only. Indeed, a metallic grounded screen such as 14 and located at a small distance from the fixed electrodes such as 8 and 10, permits to considerably diminish the residual capacitive coupling which is present between a pair of electrodes 8 and 10 at a given crosspoint, and this in the absence of a coupling electrode such as 12. The more the plane of the screen 14 is brought nearer to the plane of the electrodes 8 and 10, the greater will be the diminution of the A.C. energy transfer between these electrodes, which tends towards a minimum value when the distance between the face of the screen 14 located on the side of the electrodes 8 and 10, and the corresponding faces of the latter, has reached a value which is of the order of the distance separating these electrodes 8 and 10. Similarly, the parasitic residual couplings between fixed electrodes pertaining to adjacent rows or columns will also be considerably reduced by the adjunction of these screens 14 at a sufficiently small distance from the plane of the fixed electrodes. An effect of the screen 14 will, of course, be to increase the parasitic capacitance to ground of the fixed electrodes, parasitic capacitances which will also be present when the electrode 12 carried by the strip will effect the couplings between the electrodes 8 and 10. But the screen gives a favorable effect so as to produce a better discrimination between the desired capacitive couplings and the residual capacitive couplings. On the other hand, the smaller will be the spacing between the electrodes 12 and the electrodes 8 and 10, the tighter will be the desired capacitive coupling.

The strip 4 shown in FIG. 7 carries electrodes such as 12 only on one face. As mentioned above, it will also be possible to provide electrodes constituting another code on the opposite face of the strip. In this case these elec-

trodes, when they are not effectively used to provide a coupling will be located in front of the screen 14' of the next plate. As this screen is grounded and since the distance will be small, these electrodes on the opposite face of the strip will have little influence in case where they coincide with crosspoints where a capacitive coupling between the fixed electrodes is not desired.

The lower surface of the screens can also be provided with ribs (not shown) extending parallel to the strips 4 below the lower surfaces of the screens so that these ribs constitute guiding means for the strips.

The various plates and the intermediate screens may be stacked on a frame provided with appropriate guiding means. One may envisage, for instance, a stack of fifty plates each having twenty input conductors and ten output conductors so as to constitute a semi-permanent memory of one thousand words, each comprising ten binary bits.

It will be noted that it is not absolutely essential to arrange the two types of fixed electrodes on the same surface of the plate of insulating material. In principle it will be possible to locate them on opposite sides of this plate on condition that the thickness of the latter will be relatively small. In this case, the fixed electrodes such as 8 and 10 will be in distinct parallel planes but with a very small distance between these.

In any static translating circuit comprising various couplings between input points and output points, there evidently exists a decoupling problem in the sense that part of the energy applied to an input point and destined to reach a combination of output points characterizing this input point will be derived towards other output points due to back-up through other input points.

FIG. 8 shows a symbolic representation of the equivalent electrical circuit of a capacitive memory as described above and comprising a thousand input points A and ten output points B, each input point A being connected through series capacitances each of admittance Y towards four particular B points, two being always chosen among a first group of five B points and the other two in the second group of five B points. In this manner each point A may have one characteristic among one hundred possible characteristics.

Each A point is represented as connected to ground through an admittance Y_0 while each B point is connected to ground through an admittance Y_1 . These two admittances may be constituted by the input and the output impedances of the transmitting network and also comprise the parasitic capacitances to ground. The multiplying arrow provided with the digit 4 indicates the connections between the points A and B. Moreover, additional connections between the points A and B have been represented in dotted lines and comprise a capacitance having an admittance mY . This capacitance represents the residual coupling which exists between each A point and the six B points to which this A point is not connected via capacitances indicated by Y and corresponding to those introduced by the coupling strips.

In such a network, when a particular A point is fed by an A.C. energy source, the four B points which are associated thereto through the admittances Y will be brought to an operating potential in order to characterize the particular A point among the thousand points. However, the potential of the other six points will not be altogether equal to that of ground due to the back-up couplings mentioned above and also due to the residual coupling capacitances shown in FIG. 8.

In order to investigate the amount of parasitic couplings, i.e., the importance of the voltages at the B points which must not be activated, the eventual symmetry of the circuit must be examined in order to deduce an equivalent electrical circuit showing the importance of the parasitic couplings. The symmetry of the circuit depends not only on that of the capacitive memory shown in FIG. 8, but also on that of the input network which will be used

to couple the energy source to a particular A point among the thousand points. This system of coupling of the source towards the different A points constituting the inputs of the capacitive memory may consist in a network of gates arranged in stages in the form of a tree network whose principles is well known. This network will in fact be described later. If the network of access gates is sufficiently efficient so that it transmits only a very small part of the source energy to the other A points than that which is identified, one may separately perform the analysis of the two networks, i.e., that of the access network and the other constituting the capacitive memory.

In this case, FIG. 9 represents the equivalent electrical circuit of the network of FIG. 8 when a particular A point among the thousand is fed by an A.C. energy source. The equivalent circuit of FIG. 9 assumes on the other hand that the thousand input A points are equally distributed among the hundred possible codes provided by combinations of four B points simultaneously activated. This is an entirely ideal distribution which does not in any way correspond to practical cases in the event of a translator serving to determine the class of telephone lines, since a large number of lines may belong to the same class and be characterized by a same code. Nevertheless, these conditions of absolute symmetry enable to establish an equivalent network which at least shows the order of the magnitude of parasitic couplings.

In the case of FIG. 9, a point B_1 and a point B_0 have been shown which correspond respectively to the common potentials of the four activated B points and to the common parasitic potentials of the six B points which must not be activated. Hence, the admittance interconnecting these points B_1 and B_0 to ground must be respectively equal to $4Y_1$ and $6Y_1$ as shown in the figure. On this basis of two types of B points when the circuit is driven, the A input points are divided into five categories: those such as the driving point which are connected to four B points which must be activated, those which are only connected to three points which must be activated, and so on.

If there were only one hundred input points and a unique correspondence between each possible code and an A point, there would be a single A point (A_4) connected to the four activated B points, twelve (A_3) connected to three activated B points, forty-two (A_2) to two, thirty-six (A_1) to one, and nine A points (A_0) solely connected to B points which are not activated. As there are ten A points per code, these numbers must thus be multiplied by ten. The potential of these different types of A points is the same for all the points of a same type which permits to establish the complete network of FIG. 9. The point A_{41} represents the driving point which is connected by the admittance $4Y$ to the point B_1 and by an admittance $6mY$ to the point B_0 . The point A_4 corresponds to the other nine A points which are also connected to the B_1 and B_0 points by admittances respectively equal to $4Y$ and $6mY$, and this parallel network in the form of a T is shown in FIG. 9 and provided with multiplying arrows marked with the digit 9 to indicate the number of these T networks which are in parallel.

The T networks comprising the points A_3 , A_2 , A_1 and A_0 are easily justified from what precedes.

FIG. 10 represents a network strictly equivalent to that of FIG. 9 but in which all the points $A_{0/4}$ have been eliminated by star-mesh transformations. In addition to the direct capacitive couplings between the point A_{41} and the points B_1 and B_0 , one obtains equivalent admittances between the points B_1 and B_0 , and between each of these points and ground. The values of these resulting admittances are indicated in FIG. 10.

So as to have a potential for the point B_0 which is as small as possible with respect to that of point B_1 , it is necessary that the admittance between the point B_0 and ground should be as high as possible with respect to the admittance between the points B_1 and B_0 . This may be

obtained by relatively high values both for Y_0 and for Y_1 . In other words, the shunt impedances at the input and at the output of the capacitive network must be as low as possible. However, it is clear that as the admittances Y_0 and Y_1 are increased, the resultant admittance between the point B_1 and ground will also increase and consequently there will be an increase in the attenuation of the usual signals. Thus, it will be of interest, particularly for Y_0 , to choose a sufficiently high admittance so as to limit the effect of back-up couplings without introducing an excessive attenuation of the useful signals which would lead either to too high a level for the driving source, or to too low a level at the receiving end, in such a manner that noise and parasitic signals would become a problem and would complicate the amplifying and detecting system which must be provided for each of the B points.

If the admittances Y correspond to capacities of a few picofarads only, which will be the case particularly if the elemental surfaces of the crosspoints are relatively small, and if, for instance, the signal is constituted by a source having a frequency of 250 kc./s., Y_0 might correspond to an impedance of the order of 1500 ohms while Y_1 might correspond to an impedance of the order of 25 ohms.

The resultant admittance between the points B_1 and B_0 clearly shows the influence of m which characterizes the value of these parasitic series capacitances. If m is reasonably smaller than unity, the terms proportional to m and m^2 will become of secondary importance.

It will be recalled that the circuit of FIG. 10 is valid only in the case of absolute symmetry. In practice, however, the resultant admittances shown in FIG. 10 are rather representative. Indeed, if one considers, for instance, the most unfavorable case for the resultant admittance between the points B_1 and B_0 , i.e., when all the A points, with the exception of the driving point, are each connected to two activated B points and to two unactivated B points, the equivalent series will be equal to

$$\frac{999(2+2m)(2+4m)Y^2}{(4+6m)Y+Y_0}$$

which, when m is reasonably smaller than unity, is not very much larger than the admittance shown in FIG. 10.

The importance of the parasitic signals solely due to the capacitive memory having now been determined, the influence of the parasitic signals, due to the fact that the gate access circuit to the capacitive memory is not ideal, will now be examined.

FIG. 11 represents the principle of an access circuit of a known type in which the gates are distributed in three stages in the form of a tree. The A.C. energy source E present at point D is applied in parallel, as indicated by the multiplying arrow marked by 10, towards ten gates G_A respectively controlled at control points $P_{A0/9}$. The outputs of each of the primary gates G_A are in turn connected in parallel towards ten gates G_B which are controlled from the ten control points $P_{B0/9}$ of the second stage. In turn the outputs of the gates G_B are each connected in parallel to ten gates G_C forming the third stage of the access circuit, which gates are controlled from the ten control points $P_{C0/9}$. Finally, the outputs of the thousand gates G_C constituting the third stage correspond to the input points A of the capacitive memory.

The principle of such a gate network is well known and can be found, for example, in the U.S. Patent No. 2,724,018 issued to W. Pouliart et al., November 15, 1955. The thirty control points are associated to the eleven-hundred and ten gates in such a manner that the simultaneous presence of a control pulse at one of the control points in each series of ten opens a path between the single input point D and the particular output point A corresponding to this combination of control points. When such a control is applied to the gate network in order to realize such a connection, one may

70 75

establish the electrical circuit equivalent to that of FIG. 11 by using the method of the points having the same potential and already considered in relation to the capacitive memory (FIG. 9).

5 FIG. 12 shows the equivalent circuit of the gate network of FIG. 11 when a particular conductive path is established between the point D and the point A_{111} through three gates in cascade, all three conductive. As shown in FIG. 12, at each branch point of the gate network one goes towards a gate made conductive and on the other hand towards nine other gates of the same rank which are blocked. Due to the symmetry of the circuit one may consider that these blocked gates are all in parallel so that for the primary stage of gates G_A , for instance, the ten gates are divided into a conductive gate and nine blocked gates which have been represented by a single one in FIG. 9 with cross hatchings inside the circle symbolically representing the gate. The ten gates G_B connected at the output of the gate G_A made conductive are divided in exactly the same way as indicated in the figure, while the ninety remaining gates G_B connected to the outputs of the nine blocked gates G_A are also divided in the same proportion of 1 to 9. The distribution of the gates of the third stage is immediately deduced from the preceding considerations and for three stages of gates one reaches therefore eight types of output points $A_{000/111}$ whose respective numbers have been indicated next to the gates of the third stage.

If the attenuation of the blocked gates is not infinite, all the A outputs will thus receive a certain residual signal. So as to limit the effect of these residual signals on the capacitive memory one may impose a limiting value for the sum of these residual signals by assuming the most unfavorable case where these are superposed in phase. 35 This sum of residual voltages at the nine-hundred-and-ninety-nine A points which must not be activated can, for instance, be limited to 5% of the source voltage, i.e., approximately that which reaches the selected point. If a , b and c are the respective attenuations provided by 40 the blocked gates, depending on whether they pertain to the first, the second and the third stage, one may neglect the residual voltages at the A points reached by means of at least two cascaded blocked gates. Indeed, these residual voltages will evidently be much smaller than those obtained at the A points connected to the 45 source by means of a single blocked gate, and particularly if the values of a , b and c are relatively very small with respect to unity. In this case, only the nine points A_{110} , the nine points A_{101} , and the nine points A_{011} are left to be considered as bringing a contribution to the 50 sum of the residual output voltages. With a , b and c all three equal to 0.002, a total residual voltage equal to 5.4% of the source voltage will thus be obtained. To secure a sufficiently small value for the attenuation of the blocked gates electronic gates comprising two 55 diodes might be used.

FIG. 13 shows a gate of this type. The A.C. sinusoidal input voltage E applied to point D drives the diode gate which comprises a first series rectifier W_1 whose anode is connected to point D and whose cathode constitutes the output terminal of the gate. This cathode is also connected to a biasing potential $-E_1$ through a resistor R_1 . Moreover, this cathode of the rectifier W_1 is still connected to the control point P_a through a shunt diode W_2 whose cathode is connected to that of W_1 . Finally, one must also take into account the capacitive load at the output terminal of the gate, load represented by the condenser C_1 .

The biasing potential $-E_1$ may be equal to -12 volts when the amplitude of the signal from the sinusoidal source E is of 6 volts, while the potential of the control point P_a will normally be of $+6$ volts to reach -6 volts when it is desired to unblock the gate. Indeed, with a potential of 6 volts at terminal P_a , rectifier W_2 is conductive and rectifier W_1 is blocked. With -6 volts at

terminal P_a one reaches the reverse situation and the signals from the source E can be transmitted through the gate. In order that the gate should be efficient when it is made conductive, it is necessary that at any moment rectifier W_1 should not be biased in the reverse sense, which demands that the D.C. current drawn by R_1 should be higher than the maximum instantaneous current supplied by W_1 . This A.C. current is a function of R_1 and of the impedance offered by C_1 at the frequency used. For a frequency of 250 kc./s. and for a value of C_1 of the order of 100 picofarads, this condition leads to a value of R_1 of the order of 10 kilo-ohms as upper allowable limit with the voltages considered.

On the other hand, when the gate is blocked its attenuation is substantially proportional to the ratio between the dynamic resistance of rectifier W_2 and the reactance introduced by the residual capacitance of W_1 whose conductance can be neglected when this rectifier is blocked. The load offered by the circuit C_1R_1 may in this case be neglected. By using OA85 diodes, the dynamic resistance of W_2 is of 200 ohms, while the parasitic capacitance of W_1 is of 2 picofarads, which gives a value of $a = \frac{1}{1600}$ for a frequency of 250 kc./s.

Thus, it is seen that this value of a is more than sufficient to secure a total residual voltage of the order of 5% of that of the source. On the other hand, the attenuation provided by a gate comprising a single diode only would not be sufficient for the rather high frequencies considered due to the capacitance of the blocked diodes.

FIG. 14 represents a similar gate where there is solely one series rectifier W_3 whose cathode is connected to the control point P_c through the resistance R_2 . If a value of 1500 ohms is chosen for R_2 the attenuation of the gate of FIG. 14 will be equal to $\frac{1}{212}$ for the frequency considered.

It is particularly advantageous to realize the gates G_c (FIG. 11) of the third stage in the simplified form of FIG. 14, while the gates G_A and G_B of the first and the second stages will be realized in the form shown in FIG. 13. In this case, the total residual voltage will be equal to 5.3% of the source voltage which is satisfactory value and similar to that obtained when all the gates give an attenuation of 0.002. But, the mixed system offers the advantage that the gates G_c which are by far the most numerous necessitate only a single diode.

By referring to FIG. 15 one will now examine the useful signal transmitted by the capacitive memory. This signal depends first on the series coupling capacitance obtained at the crosspoint with the help of the coupling strip. However, particularly when using a screen such as 14 (FIG. 7) the shunt capacitance towards ground must be taken into account. By referring jointly to FIGS. 7 and 15, one may thus consider that the series coupling capacitance is divided into two capacitances of values $2C_2$ interconnected in series between the points A and B and corresponding to the capacitances between the electrodes 8 and 12, and 12 and 10. FIG. 15 shows that the junction point of these two capacitances is connected to ground through a condenser C_3 which corresponds to the capacitance between the strip electrode 12 and ground, to which the screens are connected. One may also consider the parasitic capacitances C_4 towards ground between the fixed electrodes 8 and 10 which may be assumed to be approximately equal. In principle C_4 will be of the order of half the value of C_3 .

Thus, FIG. 15 shows an A input point of the capacitive memory connected to a B output point through a capacitive network including several branches, the resistance R_3 connected to point B representing that of the detector.

The network of FIG. 15 may be simplified to the form shown in FIG. 16 where C_5 represents an equivalent series capacitance and $C_6 - C_5$ equivalent shunt capacitances.

By referring to FIG. 10 with sufficiently high values for Y_0 and Y_1 , point B_0 is practically grounded and in a general manner one may consider that the main effect of the back-up is then to introduce a parasitic shunt admittance in shunt across the detector to be activated, i.e., between point B_1 and ground. This amounts to consider that the nine-hundred-ninety-nine A points with the exception of that which is driven are practically at ground potential and consequently for the coupling circuit of FIG. 16 one may assume the most unfavorable case, that for which all the A points are connected to the four B points which must be activated. Hence, each coupling circuit from an A point other than that which is driven will introduce a parasitic capacitance equal to $(C_6 - C_5) + C_5 = C_6$ at point B.

By taking into account the shunt effect of the other circuit, the equivalent coupling circuit of FIG. 16 thus becomes that of FIG. 17.

From Thevenin's theorem this is transformed into a simple series circuit represented in FIG. 18.

If it is assumed, for instance, that C_5 is equal to 10 picofarads while C_6 is equal to 12.5 picofarads, that R_3 is equal to 25 ohms, while the R.M.S. voltage of the source of 250 kc./s. is 4 volts, a voltage of the order of 1.4 millivolts is obtained at point B. This voltage producing a small current through resistance R_3 will have to be amplified to provide a useful operating signal particularly in the case where the useful signals must operate a relay.

FIG. 19 represents a detecting circuit to be connected to point B in order to be able to cause the operation of a relay T_r corresponding to a particular B point. A low input impedance of the order of 25 ohms (R_3) may be obtained at the B point by using an OC44 transistor connected with a grounded base to constitute the first amplifying stage. The emitter of this transistor is directly connected to point B and is biased through a resistor of 5.6 kilo-ohms by a voltage of +6 volts, the base of this transistor is directly connected to ground while the collector is biased to a voltage of -6 volts through the primary winding of a transformer T_1 shunted by a tuning condenser C_7 . This condenser C_7 may be chosen so as to obtain resonance at a frequency of 250 kc./s. It may, however, be found advantageous to use a tuning condenser which is as small as possible and constituted, for instance, by the output capacitance of the OC44 transistor and the parasitic capacitance of transformer T_1 , in order to reduce the response time of the detecting circuit. The response time essentially depends on the shape of the control pulse, on the speed of response of the diodes used for the electronic gates, as well as from the Q of the transformers used in the detecting circuit of FIG. 19. This response time may anyhow be made arbitrarily small by using a sufficiently high frequency. With a frequency of 250 kc./s. a response time of the order of 10 to 15 periods of the signal frequency, i.e., 50 microseconds, may readily be obtained, but this value could be reduced by diminishing the selectivity of the detecting circuit.

Transformer T_1 steps down the voltage in a ratio which may be of the order of 20 to 1, and by way of example, the primary inductance may be of the order of 50 millihenries by using a ferrite core exhibiting an optimum Q in the neighborhood of the signal frequency. This first amplifying application stage may readily give a current gain of the order of 15.

The secondary winding of transformer T_1 is on the one hand connected to ground and on the other hand to the emitter of the second transistor CC44 also operated with a common base fashion, the latter being connected to the voltage of -6 volts through a resistor of 100 kilo-ohms and to ground through a decoupling condenser of 0.02 microfarad. The collector of this transistor is also connected to the voltage of -6 volts through the primary winding of transformer T_2 which steps down the

voltage in a ratio of two to one, its secondary winding being connected to a rectifier bridge RB using, for instance OA85 diodes. This rectifier bridge is destined to feed the output stage of the detecting circuit and provides not only a D.C. voltage, but also acts as noise suppressor by absorption of signals having a too small level. The output of this bridge is branched on a resistor of 2 kilo-ohms of which one end is grounded, while the other end is connected to another resistor of 2 kilo-ohms feeding the base of an output OC76 transistor whose emitter is grounded and whose collector goes to the voltage of -6 volts through the winding of relay Tr. The signal noise ratio may still be improved by the insertion of a suitable non-linear circuit at the input of the output stage.

In the following there is described a circuit arrangement of an autodialler by way of an example of practical application of the information storage device according to the invention.

The circuit arrangement, according to FIG. 20, shows three of a plurality of rapid-call-keys T1, T2, . . . Tn; to each of these keys of marking lead 1, 2, . . . n is assigned leading to a relay R1, R2, . . . Rn, and to which the capacitive couplings C1a . . . Cmd are connected which, on the other hand, are connected to the marking leads 1a . . . md. The code is determined by the capacitances C11a . . . Cmnd. The value of capacitance with respect to all of them is approximately the same (about 5 . . . 10 pf. (mmf.)).

If, for example, the rapid-call-key T1 is momentarily depressed then relay R1 is energized and continues to be energized over the contact r1 of its own. The stepping chain of counting relays M is started by the action of the contact r12; it energizes in a timely succession the relays K1 . . . Km; relay K1 effects the connecting-through of the evaluation lines 1a, 1b, 1c, and 1d to the evaluation amplifiers AV1 . . . AV4, and the latter are marked in dependency upon the capacities C11a, C11b, C11c, C11d which are prepared in the autodialler (only one value of capacitance C11a is shown in the example). The circuits for the four evaluation amplifiers are completed via:

Earth, s. r11, C11a (and C11b, C11c, C11d, provided that such ones are arranged), k1a (k1b, k1c, k1d), AV1, (AV2, AV3, AV4)

to the counting chain Z. The counting chain of relays M connects the relays K1 . . . Km in dependency upon the counting chain Z in a timely succession to the groups of evaluation lines 1 . . . m. On account of this, with respect to each of the digits of the positions 1 . . . m in the information preparatorily stored in the code converter by the groups of capacitive couplings C11a . . . d, . . . C11m . . . d, and expressed by an m-digit number in the decimal system, the evaluation amplifiers AV1 . . . AV4 are marked one at a time in turn in such a way that each digit is expressed in the manner known per se by way of a binary number. The counting chain Z is adapted to control a pulse generator I (source of impulses) of a likewise conventional type, which transmits trains of impulses by way of a pulsing contact i controlled thereby. The number of impulses in the trains of impulses corresponding to the individual digits is determined on the one hand by the marking of the evaluation amplifiers and, on the other hand, by the counting chain Z which is either controlled from one initial position to a coincidence with the marked evaluation amplifiers, or is stepped-on from its position determined by the marked evaluation amplifiers to a final (or end) position, or is returned (controlled backwards) to its initial position. In all cases, in dependency upon the control effected by the counting chain Z, the source of impulses supplies the impulses for the individual trains of impulses.

At the end of the last train of impulses, relay S op-

erates in dependency upon the counting chain Z, and interrupts the evaluation circuit by opening its contact s, whereupon also the stepping chain of counting relays M is returned to normal.

5 A modified type of embodiment of the circuit arrangement, according to the invention, is shown in FIG. 21; there is only provided one single evaluation amplifier AV which, in dependency upon a switching device a, b, c, d, controlled by the counting chain Z, is applied 10 in a timely succession to the individual lines 1, 2, 3, 4, leading to the contacts k1a . . . kmd connected to the individual evaluation lines 1a . . . md.

The evaluation amplifier AV receives the information 15 of each individual evaluation line . . . a . . . . . . d in each group 1 . . . m of evaluation lines in a timely succession and stores them until the counting chain Z is further stepped-on in order to evaluate the next digits. The source of impulses I controls the pulsing contact i in the manner already described hereinbefore.

The following is an exemplified description of a code. It is the type which is usually used to represent the digits 0 . . . 9, as well as the signal for starting and terminating a local call in the binary fashion.

8 4 2 1

45 FIG. 22 shows the plates or coatings of the translator in the line arrangement. The coupling is effected at the corresponding points by a metal coating according to FIG. 24 applied to a slide according to FIG. 6, and which is respectfully provided at those points which are denoted by "1," "2," "4," "8" respectively, whenever a "1" appears in the code at this point; if a "0" appears in the code then the coating according to FIG. 24 is dispensed with at this point.

55 FIG. 23 is a sectional view of the translator. The plate 15 of insulating material carries the metal coatings 1, 2, in a line- and column-wise arrangement, as may be seen from FIG. 23. The slide 4 according to FIG. 24 of insulating material is provided with the metal 60 coatings 6 according to FIG. 25, and may consist, for example, of an eloxadized aluminum sheet. A spring 16 presses the slide 4 in a definitely fixed position against the plate 15 of insulating material, and rests against grounded screens 14, 14' connecting the translator to 65 form one complete structural unit.

70 Whenever it appears to be necessary to change an information preparatorily stored in the translator—for example, a subscriber's call number—then simply the respective slide 4 has to be pulled out in the associated line of the translator and replaced by a slide provided with a coating 6 which then corresponds to the new information.

75 While the principles of the invention have been described above in connection with specific apparatus, it is to be clearly understood that this description is made only

by way of example and not as a limitation on the scope of the invention.

What is claimed is:

1. An information storage device for use in an automatic dialling system comprising a first plurality of conductors and a second plurality of conductors arranged to form a coordinate array of crosspoints, each crosspoint comprising a pair of closely spaced fixed electrodes mounted on the same side of a plate of insulating material, means connecting one of each of the fixed electrodes to one of the first plurality of conductors, means connecting the other fixed electrode of said pair to one of the second plurality of conductors, said fixed electrodes normally having a certain capacitive coupling therebetween, means for changing the said capacitive coupling comprising a strip of insulating material for each conductor of the first plurality, a plurality of auxiliary electrodes mounted on said strip, said strip movably inserted justaposed and parallel to the face of the said plate upon which the fixed electrodes are mounted so that said auxiliary electrodes overlap the fixed electrodes to change the capacity therebetween, a plurality of read-out means, there being at least one for each conductor of the first plurality, means responsive to the operation of any of said read-out means for applying a potential to the corresponding conductor of said first plurality, and means for translating the capacitive coupling

5

10

characteristics between conductors of said first plurality and said second plurality of conductors into signals characteristic of the said read-out means operated.

2. An information storage device, as defined in claim 1, in which the means for varying the capacitive coupling between a conductor of the first plurality and conductors of the second plurality at a combination of crosspoints includes means for selectively changing the combination of crosspoints at which said variations of capacitive coupling occurs.
